DESIGN FOR SUNGLASSES

Elise S. Payne, New York, N. Y.

Application October 22, 1938, Serial No. 80,622

Term of patent 3½ years

To all whom it may concern:

Be it known that I, Elise S. Payne, a citizen of the United States of America, residing at New York, in the county and State of New York, have invented a new, original, and ornamental Design for Sunglasses, of which the following is a specification, reference being had to the accompanying drawing, forming a part thereof.

In said drawing:

Fig. 1 is a top plan view of the sunglasses, showing my new design;

Fig. 2 is a front elevation; and

Fig. 3 is a side elevation.

I claim:

The ornamental design for sunglasses, as shown.

ELISE S. PAYNE.
